UNITED STATES PATENT OFFICE.

ERNEST A. WALKER, OF NEWARK, NEW JERSEY, ASSIGNOR TO WILLIAM GOLDBERG
AND ABE GOLDBERG, TRADING AS A COPARTNERSHIP UNDER NAME OF THE G. & G.
FIXTURE CO., OF NEWARK, NEW JERSEY.

DESIGN FOR A WALL LANTERN.

Application filed March 17, 1925. Serial No. 12,748. Term of patent 7 years.

To all whom it may concern:

Be it known that I, ERNEST A. WALKER, a citizen of the United States, residing at 762 Summer Avenue, Newark, in the county of Essex and State of New Jersey, have invented a new, original, and ornamental Design for a Wall Lantern, of which the following is a specification, reference being had to the accompanying drawing, forming part thereof.

Fig. 1 is a side view of a wall lantern, showing my new design. Fig. 2 is a plan

thereof with the supporting arm broken away and the supporting plate omitted.

I claim:

The ornamental design for a wall lantern, as shown.

In witness whereof, I hereunto subscribe my name, as attested by the two subscribing witnesses.

ERNEST A. WALKER.

Witnesses:

ABE GOLDBERG,
L. E. FISCHER.
